UNITED STATES PATENT OFFICE.

LLOYD GROFF COPEMAN, OF FLINT, MICHIGAN, ASSIGNOR TO COPEMAN ELECTRIC STOVE COMPANY, OF FLINT, MICHIGAN, A CORPORATION OF MICHIGAN.

ELECTRICAL HEATING UNIT.

1,138,783.

Specification of Letters Patent. Patented May 11, 1915.

Application filed January 23, 1914. Serial No. 813,934.

To all whom it may concern:

Be it known that I, LLOYD GROFF COPEMAN, a citizen of the United States of America, residing at Flint, in the county of Genesee and State of Michigan, have invented certain new and useful Improvements in Electrical Heating Units, of which the following is a specification, reference being had therein to the accompanying drawings.

The invention relates to electrical heating units particularly designed for use in cooking operations, and it is the primary object of the invention to obtain a flexible construction, or one in which the intensity and distribution of the heat may be varied according to the requirements.

In the drawings: Figure 1 is a perspective view of the unit complete; Fig. 2 is a plan view of the insulator holder for the resistor; Fig. 3 is a sectional side elevation thereof; and Fig. 4 is an enlarged section showing the retaining means for the resistor.

In performing cooking operations with electric heat it is desirable to vary the intensity, and to this end various constructions have been devised. It is, however, also desirable at times to vary the distribution of the heat, without changing either its intensity or quantity. For instance, if a large cooking utensil is used, a small quantity of heat may be all that is necessary for performing the operation, and yet if this is concentrated at the center of the utensil it may result in burning. On the other hand, if the same quantity of heat is distributed about the margin of the vessel it will perform the cooking without overheating.

With the present invention I have devised a construction in which the quantity, intensity and distribution of the heat may be variously adjusted and used to the greatest advantage in cooking operations. More specifically, I have devised a construction in which a plurality of sections of the heat resistor, included in separate electric circuits, are arranged concentrically and are adapted for either alternative or simultaneous operation.

As shown, A is a suitable stand or supporting frame; B is an insulator heat-distributing body, and C C' and C² are several sections of the resistor arranged in multiple

circuit. All of these sections are preferably arranged in grooves in the insulator body B and, as shown, a continuous spiral groove contains all three sections. The section C extends from the center outward, the section C² is adjacent to the periphery and the section C' is intermediate the sections C and C². The electrical resistance of these respective sections is preferably equal, so that there will be the same heat generation with any one of the sections, but with varying effect, due to difference in distribution. For controlling the circuits, each is preferably provided with an independent switch, and these switches D D' and D² may be mounted upon the stand A, as shown. There are also provided terminal contacts E and E' for connection with the external circuit.

With the construction as described, in operation, where a cooking utensil is used, the bottom of which is equal in diameter to the body B, the operator may produce varying effects by the alternative use of the several resistor sections. If intensity of heat at one point is desired, the central section C is employed, for this has all of its length concentrated in the smallest area. If, on the other hand, it is merely desired to maintain a low heat in the entire vessel, the outer section C² is placed in circuit and the heat generated will be distributed with lesser intensity at any one point. An intermediate effect may be obtained by placing in circuit the resistor section C', while still other effects are obtained by operating any two or all three of the sections in unison.

In addition to obtaining the varied effects as above described, my construction is capable of obtaining the same effects as with alternate series and multiple connections of resistor elements, or by the use of an external rheostat; but the construction is very much simplified by dispensing with such arrangements.

The resistor is preferably wound in spiral form and the spiral winding then introduced into the spiral groove, as shown. To retain the resistor in this position inwardly-projecting lugs F are preferably arranged at intervals along the spiral groove, and which, as shown in Fig. 4, prevent accidental displacement of the resistor from the groove.

What I claim as my invention is:

1. An electrical heating unit, comprising

an electrical insulating, heat-distributing body having a groove in one face thereof, separate overhanging projections extending from the sides of said groove, and a coiled 5 resistor within said groove and engageable with said overhanging projections.

2. An electrical heating unit, comprising an electrical insulating, heat-distributing body having a groove in one face thereof, 10 inwardly-projecting lugs arranged at intervals along said groove, and a coiled resistor within said groove and engageable with said lugs.

3. An electrical heating unit, comprising 15 an electrical insulating, heat-distributing body having a spiral groove in one face thereof, overhanging projections extending from the sides of said groove in a radial line from the center of said body, and a 20 coiled resistor wound spirally within said

groove and engageable with said overhanging projections.

4. An electrical heating unit, comprising an electrical insulating, heat-distributing body having a spiral groove in one face 25 thereof, inwardly-projecting lugs arranged at intervals along said groove, a resistor wound spirally within said groove and engaging said lugs, said resistor being divided into a plurality of sections concentric with 30 and surrounding one another, and means for closing circuit alternatively through said sections.

In testimony whereof I affix my signature in presence of two witnesses.

LLOYD GROFF COPEMAN.
